KNITTING MACHINE

Robert E. Mate and Nicholas Scardino, Philadelphia, Pa., assignors to Frank M. Titelman, Philadelphia, Pa.

Application October 29, 1932, Serial No. 640,202

11 Claims. (Cl. 66—155)

This invention relates to circular knitting machines and more particularly to those provided with means for selectively controlling the operation of the cylinder needles for the purpose of 5 making designs and other forms of special stitching in the work by the use of the well-known jacquard apparatus in which, through the medium of perforated cards and suitable other mechanisms, the needles which are to be utilized for 10 making stitches are selectively put in condition to be actuated by the cylinder cams in the desired predetermined sequence.

Machines of this character are commonly utilized for manufacture of sweaters, golf hose, 15 and other articles in which fancy designs resulting either from variations in the type of stitches made by the cylinder needles or from variations of the color of the thread of such stitches are desired, a plurality of cards being employed in 20 connection with each machine and so arranged as to permit the pins of the needle levers to engage adjacent card carrying drums in predetermined sequence to produce the required sequential action of the corresponding needles. In such machines 25 the several drums are ordinarily driven by suitable gear trains from the lower bevel gear ring which is in turn actuated through suitable bevel and spur gears from the cam race ring. Thus, 30 since the latter is in continuous operation while the machine is being used for knitting, and necessarily must be for the needle cams to be rotated and the needles to be actuated in their proper sequence, in the machines heretofore used the card drums referred to have likewise been maintained in continuous operation even when they 35 were not being used, as when the machine is being used for plain knitting, either with or without intermittent interpolation of design knitting.

40 As a result, it has heretofore been necessary in design knitting for the design to be continuously repeated or else for the plain work intervening between successive designs to provide the same space as that occupied by the design, or a multiple thereof, in order that the knitting of the design might thereafter be resumed, when desired, at the proper point. It will be understood by those skilled in the art that this requirement results from the continuous operation of the endless 45 jacquard cards, making the completion of what may be termed a "jacquard cycle" necessary each time one such cycle is begun in order that when the mechanism is again placed in condition for knitting a design, the commencement of such 50 knitting will make the initial stitches of the design 55

rather than some other stitches intended to be made at some point later in the pattern.

A practical disadvantage arising from this condition and which has recently become of considerable force due to the large demand for 5 knitted sweater fabrics and the like having relatively wide design bands or areas, has been the impossibility of knitting the sweater bodies or other tubular fabrics of any desired predetermined length irrespective of the relation between 10 such lengths and the length occupied by the design. Thus, for example, if a design of 12 inches in width is employed, it has been necessary to make the length of the sweater bodies some exact 15 multiple of 12 inches in order to have the design occupy the desired position in the body, so that to manufacture a 28 inch sweater body having a 12 inch design, the body had to be knit to a length of 36 inches, usually with 12 inches of plain knitting above and below the design, and the excess 20 8 inches of plain work then cut off from either the top or the bottom and discarded, since the knitting of this excess amount of plain work was required by the necessity of completing the jacquard cycle to permit the design to occupy its 25 proper position in the succeeding sweater body.

A principal object of our invention, therefore, is to provide an improved driving and controlling means for the jacquard drums of a circular knitting machine which will permit the knitting of a 30 design to be discontinued upon the completion thereof and thereafter resumed at any desired point in the course of subsequent knitting irrespective of the amount of plain knitting intervening between the two design areas.

Another object of our invention is to provide a single unitary control for the jacquard drive of such a machine whereby the lever release control mechanisms ordinarily employed for holding the needle controlling levers in non-operative 35 position when plain knitting, as distinguished from design knitting, is in progress, may be eliminated entirely from the machine and the energy loss and wear and tear on the machine heretofore resulting from their operation thus obviated.

A still further object of the invention is to provide means whereby the body of a sweater or like article being knitted on a circular knitting machine with the aid of jacquard mechanisms may be finished off at any desired length and another 40 body of the same length and having its design in the same relative position may thereafter be subsequently knitted on the same machine entirely 45 automatically and irrespective of the relative lengths of the design and of the body.

35

40

45

50

55

Another object of the invention is to provide means for controlling the operation of the jacquard cards in such manner that the drums on which they are carried are maintained at rest 5 during the knitting of plain work and are therefore rotated only at such times as the demand for a design in the work requires actuation of the levers to control the cylinder needles, our invention further including the provision of means for 10 continuously actuating the control card through the drum ordinarily provided for the purpose, independently of the operation of the jacquard drums and without in any way being affected by their use or non-use.

15 A still further object of the invention is to provide means whereby the operation of the jacquard drums may be initiated or discontinued at any desired predetermined point automatically in response to suitable perforations in the control card 20 through the instrumentality of the lever release throw cam ordinarily provided on the cam section ring of the machine and heretofore customarily utilized for the purpose of actuating the lever release control mechanisms in controlling the engagement of the levers with the jacquard cards.

Other purposes, objects and advantages of our invention will hereinafter more fully appear or will be understood by those skilled in the art from the following description of a preferred embodiment thereof during which reference will be had to the accompanying drawings:

In the ordinary circular jacquard knitting machines of the type to which reference has been made, the control drum and the several jacquard 35 drums are provided with individual gear trains interconnecting them with the bevel gear ring in such way that they are all actuated simultaneously and continuously while the bevel gear is being driven from the cam ring during the operation 40 of the machine and a lever release bracket is provided for raising and lowering each bank of jacquard levers with respect to its adjacent drum and card when, in response to suitable perforations in the control card, the lever lift cams are 45 actuated. Thus, when changing from plain knitting to design or pattern knitting, the control card is effective to so position the lever release throw cam that a complete revolution of the cam section ring on which it is disposed causes the successive actuation of each of the lever lift cams to drop the levers to position for engagement with the jacquard cards, the levers being again raised, through a substantially similar action, when plain knitting is to be resumed.

50 In accordance with our invention we provide a separate and independent drive, taken off the main driving shaft, for the control drum which is thus continuously rotated when the machine is operating on either plain or design work while the bevel gear ring referred to is utilized only for driving the jacquard drums; furthermore, we interpose a releasable control in the drive of the bevel gear ring and so arrange the actuating elements of the control that certain of the lever release control mechanisms heretofore instrumental in effecting the raising and lowering of the lever release brackets are utilized for the purpose of actuating said control. Thus the bevel gear ring and the jacquard drums are normally rotated only 55 during design knitting and remain at rest while the machine is knitting plain fabric. In consequence, considering the machine as heretofore constructed and as compared with a similar one embodying our invention, in the latter all lever release controls and control brackets are elim-

inated, the jacquard drums are normally driven only when required for the purpose of knitting a design or pattern and suitable mechanism, preferably that heretofore utilized for raising and lowering one of the lever release brackets, is employed for the purpose of actuating the bevel gear ring drive control. To this end such mechanism is desirably arranged so as to be responsive to perforations in the control card for initiating or terminating design knitting by starting or stopping the jacquard drum drive whereas this result has heretofore been effected through lowering and raising the jacquard levers while the drums were kept in motion.

15 Referring now to the drawings, Fig. 1 is a top plan view, partly broken away into horizontal section, of a large circular jacquard knitting machine embodying one form of our invention, the thread carrier, needles and several other associated parts being omitted, since they form no 20 part thereof and may be of usual and well known construction. Fig. 2 is an enlarged fragmentary side perspective view of the drive shaft side of the machine showing our improved driving means for the control card, and Fig. 3 is a still further 25 enlarged fragmentary perspective view of the opposite side of the machine showing our automatic jacquard drum drive control. In the several figures, like characters are used to designate the same parts.

30 While we have indicated in the drawings a machine of a usual type in which our invention may be advantageously employed, it will be understood we do not thereby imply that its use is in any way confined to machines of this specific 35 character as there are many other types of circular knitting machines which permit the use of or are provided with jacquard controls in connection with which our invention may be utilized with corresponding advantage.

40 Thus we have merely diagrammatically indicated in Fig. 1 the general construction of a machine having twelve banks of jacquard levers L with a drum D and card C for each, the machine being thus particularly adapted for use in making 45 sweater bodies. The machine is actuated from a driven pulley 1 suitably geared to a shaft 2 driving a spur gear 3, which engages the cam section ring gear 4 carried by the cam section ring R in such way as to rotate the latter in a counter-clockwise direction as viewed in Fig. 1. On the opposite side of the machine a substantially similar spur gear 8 meshing with the gear ring 4 drives a vertical shaft 9 to which is non-rotatably keyed 50 or otherwise secured in accordance with our invention, a clutch half 10 slidably therealong and adapted for engagement with a complementary clutch half 12 integral with a bevel pinion 13. The latter meshes with the customary gears (not shown) provided for driving the lower bevel gear 14 and thus the jacquard drums D, driven therefrom in the usual way. As will be clearly 55 apparent from Fig. 3, the rotation of the bevel pinion 13 in correspondence with the rotation of the shaft 9 when the machine is operating thus depends on the position of the sliding half 10 of the clutch with respect to the pinion. The sliding clutch half 10 is controlled by a fork 15 carried by a vertical rod 16 slidably supported in the sleeve 17 of a bracket 18 which may be bolted 60 or otherwise secured to an adjacent drum frame 19 or any other convenient point. The rod 16 is provided at its upper end with an outwardly projecting arm 20, a collar 21, secured to the rod by a set screw holding one end of the arm in position 65 70 75

thereon, while the other end of the arm is secured to the lower end of an adjacent lever bracket lift rod 22 by a set screw 23 after removal of the usual lever release bracket from the bracket lift rod. 5 The rod 16 is surrounded by a coil spring 25 under compression between the fork 15 and the supporting sleeve 17 to insure the positive inter-engagement of the clutch halves when the arm is released from the raised position shown in 10 Fig. 3.

A clutch release control 30 is provided, which may conveniently be of corresponding design to the usual lever release control normally used for actuating the lever release brackets and is actuated in the customary way from the throw cam 31 ordinarily situated on the cam section ring R, as shown in Fig. 3. The position of the throw cam is determined in the usual manner by a control lever (not shown) adapted to engage the throw cam-raising cam 32 to thereby lift the throw cam 31, the positioning of the control lever being determined in the customary way by the perforations in the control card; thus when the throw cam is raised the turning cam 33 of the clutch release control 30 is rotated through one-sixth revolution each time the throw cam engages it. As one-sixth revolution of the turning cam 33 actuates the lift cam 34 to either raise the clutch arm 20 from lowered position or permit it to descend from raised position, its actuation in response to the action of the throw cam either engages or disengages the clutch halves 10, 12, depending upon their prior status.

Inasmuch as the drum P carrying the master control card M has heretofore ordinarily been driven from the bevel ring gear 14 through a geared drive generally similar to the jacquard card drive in the ordinary machine; and, in accordance with our invention, the bevel ring gear rotates only during design knitting, we provide, furthermore, an independent drive to maintain rotation of the control card drum P continuously during the knitting process irrespective of whether the bevel ring gear is being rotated or not, thus permitting the knitting of plain work to be carried out to any predetermined desired extent, depending on the perforations in the control card; when desired, the jacquard mechanisms remaining inoperative during such knitting through disengagement of the clutch 10, 12.

As the control card bracket B is usually arranged fairly close to the main drive shaft of the machine, the control drum P may very conveniently be driven therefrom and we may thus, 55 as shown in the drawings, provide a pair of rotatable shafts 35, 36 mounted in suitable brackets 38 secured to the bed of the machine, the shaft 35 being provided at one end with a spur gear 40 secured thereto by a set screw 41 and engaging a similar spur gear 42 secured to the drive shaft 2 by a set screw 43 while the opposite end of the shaft 35 is provided with a bevel gear 45 abutting a spacer 46 and engaging a similar bevel gear 47 secured to the shaft 36. The latter, provided with 60 a spur gear 48 engaging a gear train 50, thus drives the control drum P in suitably timed relation with the rotation of the shaft 2 at all times during the operation of the machine.

The manner of operating a jacquard knitting machine when modified and arranged in accordance with our invention and as hereinbefore described, is not substantially different from that of a machine of like character but devoid of our improvements since the release and/or engagement of the jacquard control clutch is effected by

actuation of the throw cam in precisely the same manner as the several lever releases are normally actuated thereby, so that no change in the perforations of the control card or in the jacquard cards is required. Furthermore, since upon engagement of the jacquard clutch the operation of all the jacquard drums is initiated simultaneously and likewise terminated simultaneously on release of the clutch, the knitting of the design by the needles at all of the feeds is begun and ended simultaneously rather than successively as when the levers are successively lowered and raised during complete rotations of the cam section ring in accordance with the prior practice. It is moreover evident that in accordance with our invention the jacquard mechanisms are maintained entirely inoperative during the knitting of plain work and thus unnecessary wear and resultant rapid destruction of jacquard cards and other parts is avoided while an amount of driving energy is saved substantially equivalent to that heretofore required for continuously actuating these parts during plain knitting when they were producing no effect upon the work.

The control card is of course desirably so perforated that the lever operating the throw cam raising cam 32 is actuated to raise the throw cam 31 for that revolution of the cam ring R corresponding to the knitting course in which it is desired to begin the design in the work thereby effecting engagement of the jacquard clutch, and is again so actuated upon completion of the design as to disengage the clutch, thus interrupting the movement of the jacquard cards when their respective drums are in such position that a repetition of the design will be initiated upon subsequent reengagement of the clutch with consequent rotation of the drums. It is thus apparent that any desired amount of plain knitting may intervene between successive designs irrespective of the width of the design or the relation between such width and the width of the intervening plain knitting and also that, when desired, the design may be repeated any number of times either with or without the interpolation of plain knitting.

It will furthermore be apparent that the use of our invention tends to the general simplification of the machine as a whole, as it eliminates all of the usual lever release brackets and lever release control mechanisms which are frequently subject to breakage and are relatively expensive to replace. In lieu thereof we employ but a single mechanism, conveniently of generally like nature, to control the position of the clutch from the cam ring, which tends not only to lower the initial cost of the machine but its maintenance expense when in use, while our improvements as a whole permit the placing of the design wherever desired in the fabric without regard to the length of the plain knitting lying on either side thereof, with consequent frequent saving in manufacturing cost of the finished sweaters or other articles produced on the machine.

Although we have herein described our invention with considerable particularity and with special reference to its application to a circular sweater body knitting machine provided with twelve jacquard drums and their associated mechanisms, it is to be understood that it may with equal facility be employed in other sizes and types of knitting machines and in other machines employing jacquard mechanisms and that changes and modifications in the specific form of the various mechanical elements utilized

and which will readily occur to those skilled in the art may be made without departing from the spirit and scope of the invention as defined in the appended claims.

5 Having thus described our invention, we claim and desire to protect by Letters Patent of the United States:

1. In a knitting machine comprising a jacquard drum, a cam section ring and means for driving said ring, means for driving the drum including a clutch operable to interrupt said drive, and means associated with said cam section ring for actuating the clutch to thereby cause rotation or stoppage of the drum.

10 2. In a machine for the manufacture of textile fabric comprising a rotatable cam section ring and a jacquard card operative to effect the production of a design in the fabric manufactured by the machine, means for driving the card including a clutch operable to interrupt said drive, actuating means for said clutch, and means associated with said cam section ring operable to actuate said actuating means to thereby effect alternative engagement and disengagement of the clutch to intermittently drive the card in predetermined timed relation with the rotation of the cam section ring.

15 3. In a machine for the manufacture of textile fabrics comprising a cam section ring, driving means therefor, a movable control card actuated by said driving means and a plurality of jacquard cards operative to effect the production of a design in the fabric manufactured by the machine, means for driving the jacquard cards including a clutch arranged to interrupt said drive when disengaged, actuating means for said clutch, and means associated with said cam section ring and controlled by said control card operable to engage said clutch actuating means to thereby effect successive engagement and disengagement of the clutch to intermittently drive the jacquard cards in predetermined timed relation with the movement of the control card.

20 4. In a circular knitting machine comprising a rotatable cam section ring and a plurality of jacquard cards adapted to control the character of the knitting effected by the needles of the machine, driving means for said jacquard cards including a clutch disengageable to interrupt said drive, a throw cam carried by the cam section ring and means engageable therewith operable to effect successive engagement and disengagement of the clutch to thereby successively initiate and interrupt the operation of the jacquard 25 cards.

25 5. A circular knitting machine comprising a control drum adapted to carry a control card, means for continuously driving the drum while the machine is in operation, a plurality of jacquard drums, means including a clutch operative when the clutch is engaged to drive all of the jacquard drums simultaneously, a cam section ring, clutch engaging and disengaging means, and means carried by the cam section ring for actuating said clutch engaging and disengaging means in correspondence with the movements of the control card to thereby start and stop rotation of the jacquard drums in timed relation with its movement over the control drum.

30 6. A circular knitting machine comprising a control drum adapted to support a control card, means for driving said drum continuously during the operation of the machine, a cam section ring, means for driving said ring continuously during the operation of the machine, a bevel gear

35 ring, a plurality of jacquard drums interconnected with the bevel gear ring each adapted to support a jacquard card, means including a clutch operative when the clutch is engaged to drive the bevel gear ring to thereby rotate all of the jacquard drums simultaneously, means for engaging and disengaging said clutch, and means carried by the cam section ring for actuating said clutch engaging and disengaging means in coordinated relation with the movement of the control 40 card on its drum to thereby cause all of said jacquard drums to simultaneously move their jacquard cards at predetermined intervals during the progressive creation of the knitted fabric by the machine.

45 7. A circular knitting machine comprising in combination a plurality of jacquard drums each adapted to support a jacquard card, a control drum adapted to support a control card, a cam section ring and ring gear, means for driving said ring gear, a bevel gear ring, driving mechanism between the bevel gear ring and each of the jacquard drums, means including a clutch interposed between said bevel gear ring and the ring gear operative when said clutch is engaged to drive the bevel gear ring and thereby cause all the jacquard drums to rotate simultaneously, means associated with the cam section ring for engaging and disengaging said clutch, means independent of the bevel gear ring for driving the control drum, and means actuated through the medium of the control card carried by the control drum for actuating said clutch engaging and disengaging means.

50 8. A circular knitting machine comprising in combination a cam section ring, means for driving said ring, a bevel ring gear, a plurality of jacquard drums each adapted to support a jacquard card, means for driving all of said drums simultaneously from said bevel ring gear, means for driving the bevel ring gear from the cam section ring including a clutch operable to interrupt said drive, means operable through the revolution of the cam section ring for engaging and disengaging said clutch, a control drum adapted to support a control card, means independent of the bevel ring gear for driving said drum continuously while the machine is in operation, and means actuated from the control card carried by the control drum for actuating the clutch engaging and disengaging means to simultaneously start and stop all of the jacquard drums in timed relation with the movements of the control card.

55 9. A circular knitting machine having a control drum adapted to actuate a control card, a plurality of jacquard drums each adapted to actuate a jacquard card and means for driving all of said jacquard drums simultaneously, a clutch interposed in said last mentioned means operable to connect and disconnect said means with said drums, means for driving the control drum continuously during operation of the machine, a cam section ring and driving means therefor, and means associated with the cam section ring operable to actuate said clutch to start and stop the jacquard drums in predetermined timed relation to the movements of the control card on the control drum to thereby initiate and discontinue jacquard knitting at predetermined intervals in the knitted fabric as it is progressively created by the machine.

60 10. The combination with a circular machine comprising a rotatable cam section ring, a throw cam carried thereby, actuating means for the throw cam, a plurality of jacquard drums and a

bevel gear ring operable to drive said drums, of driving means interposed between said cam section ring and said bevel gear ring operable to effect rotation of said bevel gear ring in timed relation with the rotation of the cam section ring and including a clutch, and means adapted to engage said throw cam to effect intermittent disengagement of said clutch to thereby intermittently interrupt the rotation of the bevel gear

10 ring and jacquard drums.

11. The combination with a circular knitting

machine comprising a rotatable cam section ring, a throw cam carried thereby a plurality of jacquard drums and driving gears therefor, of driving means including a clutch operable when engaged to drive said driving gears from the cam section ring, means for controlling the clutch and means adapted for engagement by the throw cam for automatically actuating said clutch controlling means.

ROBERT E. MATE. 10
NICHOLAS SCARDINO.
